Des. 193,355
Patented Aug. 7, 1962

193,355

CLAMP FOR CONCRETE FORMS OR THE LIKE

Jesse J. Lambert, Los Angeles, Calif., assignor to
Irwin A. Moon, Jr., and Philipp B. Martin

Filed Dec. 16, 1960, Ser. No. 63,241

Term of patent 14 years

(Cl. D51—1)

FIG. 1

FIG. 2.

FIG. 3.

FIG. 4.

FIG. 5.

FIGURE 1 is a perspective view of a clamp for concrete forms or the like showing my new design;

FIGURE 2 is a front elevational view thereof;

FIGURE 3 is a rear elevational view thereof;

FIGURE 4 is a side elevational view thereof; and,

FIGURE 5 is an end elevational view thereof.

I claim:

The ornamental design for a clamp for concrete forms or the like, substantially as shown.
